(21) Appl. No.: **29/137,240**

(57) **CLAIM**

(22) Filed: **Feb. 15, 2001**

The ornamental design for a stud welding user interface, as shown and described.

(51) LOC (7) Cl. **15-09**

DESCRIPTION

(52) U.S. Cl. **D15/144; D10/103; D10/125**

FIG. 1 is a perspective view of a stud welding user interface showing of our new design; and,

(58) Field of Search D10/103, 125;
D15/144, 144.1, 144.2; 219/132, 130.1,
130.5, 137 PS, 130.4, 98

FIG. 2 is a front elevational view of the stud welding user interface.

(56) **References Cited**

The broken line showing is for illustrative purposes only and forms no part of the claimed design.
